ELECTRIC SWITCH

William Earl Brown, Anderson, Ind., assignor to
 General Motors Corporation, Detroit, Mich., a
 corporation of Delaware

Application May 21, 1947, Serial No. 749,474

5 Claims. (Cl. 200—156)

1

The present invention relates to electric switches and more particularly of the push and pull type by which to and fro motion of the plunger causes a switch to close a circuit.

An object of the present invention is to provide a switch in which an actuating plunger drives a switch operating ratchet wheel two steps in the same direction of rotation in response to two successive opposite movements of the plunger.

Another object of the present invention is to provide an indexing mechanism that will have a positive action but at the same time can be actuated with the minimum of effort. The indexing mechanism is such that it will maintain the plunger of the switch in either of its actuated positions regardless of shocks or vibrations that may be applied to the switch housing or the control structure.

Another object of the present invention is to provide an improved switch mechanism by which each movable contact of several is moved to four successive "on" positions and then to two successive "off" positions, but always having two of the several movable contacts in "on" position at the same time. This distributes the contact duty among the several movable contacts so that they are capable of use for long periods without replacement.

Further objects and advantages of the present invention will be apparent from the following description, reference being had to the accompanying drawings wherein a preferred embodiment of the present invention is clearly shown.

In the drawings:

Fig. 1 is a plan view of the switch embodying the present invention.

Fig. 2 is a sectional view taken on line 2—2 of Fig. 1.

Fig. 3 is a view similar to Fig. 1 with the terminal plate and the movable contact of the switch removed with the plunger in one of its positions.

Fig. 4 is a view similar to Fig. 3 but showing the plunger in another position.

Figs. 5 and 6 are sectional views taken on lines 5—5 and 6—6, respectively, of Fig. 3.

Fig. 7 is a plan view of a movable contact used in this switch.

Fig. 8 is a diagrammatic view of the switch, the elements being projected upon a single plane to illustrate the relation of the cooperating parts.

Referring to the drawings 20 designates a switch casing having an upwardly extending sleeve 21, a partition 22 and a housing 23 having

2

an open side closed by a closure or block 24 of insulating material. The open end of the housing is recessed to provide a peripheral shoulder 25 and a peripheral flange 26. The closure is held against the shoulder by deforming the flange 26 at several places against the outer surfaces of the cover. It is to be understood that other means may be used to secure the block to the housing. For example, the housing 23 could be formed with tangs and bent over exterior surface of the closure 24 to force the closure against the rim of the housing.

The bottom wall 27 of the housing 23 and the closure 24 are provided with recesses in direct alignment with each other to support a rod or shaft 28. The shaft loosely supports a driving or ratchet wheel 30 stamped from sheet metal. In this instance the wheel is formed with six equally spaced openings 31, each opening having two straight side edges 31a which act as ratchet teeth.

A plunger 32 stamped from heavy sheet metal is formed with an enlarged portion 33 and a reduced portion 34 to form a shoulder 35. The reduced portion 34 extends through an aperture 36 formed in the partition 22. This opening is complementary to the contour of the reduced portion and assists in guiding the plunger 32 into steady straight line movements of the plunger. The enlarged portion 35 of the plunger has a slot 37 which straddles the shaft 28. The slot is also adapted to straddle a projection or lug 38 formed on the interior of the bottom wall 27 of the housing 23. The lug 38 will extend into the slot 37 upon downward movement of the plunger to assist in guiding the plunger 32 in its straight line movement. The enlarged portion 33 of the plunger 32 is provided with two projections 40 and 41 one on each side of the slot 37. The projections 40 and 41 are tapered as shown in Fig. 5 and Fig. 6. The taper of the projection 40 is opposite to that of the projection 41 to be described.

The wheel 30 is provided with a tongue 42 bent at an angle to the plane of the wheel and fits into a slot 43 of a movable carrier 44 of non-conducting material and is loosely supported on the shaft 28. The tongue 42 drives the movable carrier around the shaft 28. The face of the movable carrier 44 adjacent the closure supports a bridging member 45, see Fig. 7, having three arms 46 extending radially from a central portion 48. Each arm is provided with a detent portion 49. The contact 45 is also provided with a plurality of tongues 50 each of which extend into suitable openings 51 provided by the carrier, to anchor

the bridging member thereon. The detents 49 formed on the arms are so shaped to receive rounded heads of conducting rivets or distributing terminals 55, 56, 57 and 58 carried by the block 24 and rounded bosses 59 formed on the inner face of the closure 24. The rivets are arranged consecutively in a circular row and hold conducting plates in recesses provided on the outer face of the block 24. The rivets 55, 56, 57 and 58 are connected to conducting plates suitably supported on the exterior face of the cover or block 24. In this instance the rivets 55 and 56 extend through the closure 24 and through suitable openings in a conducting plate 59a. The rivets 55 and 56 are pinned over to hold a plate 59a firmly in a recess in the exterior face of the closure 24. The plate 59 mutually connects the two rivet terminals 55, 56 and is connected with the current supply. The rivets 57 and 58 respectively extend through the closure 24 and through openings in independent conducting plates 60 and 61 and riveted over to hold their respective plates firmly in recesses provided on the exterior face of the closure 24. The terminals 57 and 58 are the current distributing terminals.

It will be noted that the rivet heads 55, 56, 57, 58 and the bosses 59 are arranged successively in a circular row to provide six positions to which the movable contact can be rotated. The terminals 55, 56, 57 and 58 cooperate with the arms 49 to establish circuits alternately between the current supply terminals 55, 56, and the current distributing terminals 57 and 58.

A compression spring 70 interposed between the movable carrier 44 and the ratchet wheel 30 operates in two directions. When the closure 24 is assembled to the housing 23 the spring 70 will be compressed. The spring urges the carrier 40 and contact 45 toward the closure and the ratchet wheel 30 against the enlarged portion 33 of the plunger 32. The spring 70 provides the necessary pressure to effect good contact engagement between the movable contact 45 and the rounded head of the terminals and yet permits relative axial movements of the wheel 36 and movable contact 45 on the shaft 28.

Referring to Fig. 2, it will be observed that in this instance that the plunger 32 must be actuated manually to either of its positions. The plunger is prevented from moving accidentally from either of its actuated positions due to vibrations or jars by the detents 49 provided by the bridging member 45. The detents 49 set firmly on the rivets in any position. If desired an indexing mechanism may be provided to assist in preventing accidental movement of the plunger 32. One form of the indexing mechanism which may be used comprises a bearing member or ball 80 which is urged into one or the other of detents 81 provided in reduced portion 34 of the plunger 32, by a spring 82. The spring 82 is housed within a passage 83 provided in the partition 22 and held therein by a screw plug 84.

The reduced portion 34 of the plunger is attached at its upper end to a cap 85. In this instance the reduced portion 34 is riveted at 86 to the cap 85. The cap 85 telescopes the upper end of the sleeve 21 and thus assists in guiding the plunger in its reciprocable movements.

The operation of the switch is as follows: When the operator applies pressure to the cap 85, as viewed in Fig. 3, the plunger will move downwardly in a straight line through the cooperation of slot 37 and projection 38, plunger portion 34 and opening 36, and the sleeve 21 and 75

the cap 85. When the plunger has moved a certain distance the projection 40 will engage one of the straight edges 31a to drive the wheel 30 in a clockwise direction. After the plunger has moved its full downward stroke the wheel 30 and contact 45 will be rotated one step equal to one-sixth of a revolution. As the plunger is moved downwardly the projection 41 will engage a narrow strip of metal between two adjacent openings 31 to rock slightly the wheel toward the carrier. When that happens the spring will be compressed until the projection 40 registers with another opening 31. When the plunger has reached its extreme downward movement as shown in Fig. 4, the plunger 32 is manually actuated to move the plunger from the position shown in Fig. 4 to that shown in Fig. 3, the projection 41 will engage a straight edge 31a to move the wheel 30 another step in the clockwise direction which is equal to one-sixth of a revolution. During the last mentioned step of rotation the projection 40 will slide over another narrow strap between two adjacent openings 31. The projection 40 will cause the wheel to tilt slightly until the projection 40 registers with another opening 31. When the shoulder 35 engages the under side of the upper wall 90 of the housing 23 limit of outward movement of the plunger 32 is reached.

It will be observed by reference to Fig. 7, that two of the contact arms 49 of the movable contacts engage stationary contacts and the other arm engages one of the bosses 59. When the plunger 32 is actuated in either direction the movement of the movable contact 48 and the wheel 30 will be in the direction of the arrow A. Thus each contact arm will have four consecutive "on" positions and two consecutive "off" positions. By this arrangement the duty of the contact arms is distributed so that they will have longer life.

The switch thus described may be mounted on a suitable support 91 such as the dash board of an automobile. The support 91 has a suitable opening 92 through which the sleeve 21 and the cap 85 pass. The sleeve 21 is provided with a shoulder 93 and has a threaded portion 94. Thus when the cap is inserted through the opening 92 the shoulder will engage the underside of the support 91 while the threaded portion 94 projects through the opening. When a nut 96 is screw-threaded upon the outer portion the shoulder 93 will bear against the underside of the support to hold firmly the switch to the support 91.

The present switch mechanism has been described by which each movable contact of several is moved to four successive "on" positions and then to two successive "off" positions but always having two of the movable contacts in "on" positions at the same time. It will be obvious to persons skilled in the art that it will be equally easy to use the present switch mechanism where only two stationary terminals are needed in which case, of course, the switch would be of the "off-on" type. Further, if desired, a return spring could be inserted between the partition 22 and the cap 85. Thus when the cap is pushed in against the action of the spring the spring would return the cap to its outermost position upon release of the force which pushed the cap inwardly.

While the embodiment of the present invention as herein disclosed, constitute a preferred form, it is to be understood that other forms

might be adopted, all coming within the scope of the claims which follow.

What is claimed is as follows:

1. A switch comprising in combination; a casing; a closure for the casing carrying stationary contacts; a stud supported by the casing and closure; a manually operated actuator slidably supported by the housing perpendicular to the axis of the stud, said actuator having a slot through which the stud projects to guide the actuator in straight line movements; a disc rotatably supported on the stud; ratchet provisions provided by the actuator on each side of the slot and capable of extending into openings provided by the disc to move the disc step-by-step in one direction of rotation only upon opposite movements of the actuator; a carrier mounted for axial and rotary movements on the stud and carrying a bridging member adjacent the stationary contacts; means provided by the disc for driving the carrier whereby the carrier rotates with the disc at all times; spring means disposed between the carrier and disc tending to urge them apart and maintain the ratchet provision effective; and means for yieldingly holding the actuator in any one of its actuated positions.

2. In combination; a casing; a closure for the casing; a rod within the casing having one end supported in the casing and having the other supported in the closure; a slotted plunger reciprocably mounted in the casing with the slot of the plunger straddling the rod; an actuator rotatably supported on the rod and provided with a series of openings arranged in a circular row; ratchet provision provided by the plunger on each side of the slot, each provision extending into an opening whereby the plunger rotates the actuator in one direction only by two successive opposite movements of the plunger; and spring means for urging the actuator against the plunger for maintaining the ratchet provisions effective.

3. In an electric switch, having six positions arranged in a circular row, four of said positions including stationary contacts arranged consecutively with two of the adjacent contacts being mutually connected; a rotary disc carrying a contact having three fingers with one of the fingers always engaging one of the mutually connected contacts and another finger engaging one of the other contacts, an actuator driving the disc, said actuator rotatably mounted with respect to the carrier and having ratchet openings arranged in a circle; a reciprocating plunger provided with two projections adapted to extend into respective openings of the disc on opposite sides of the center of the actuator to impart two movements in the same direction of rotation to the actuator

by two opposite movements of the plunger; and spring means for urging the actuator against the plunger to maintain the ratchet provision effective.

5 4. A switch comprising, stationary contacts arranged in a circular row; a movable contact rotatably supported relative to the stationary contacts; means mounted for axial and rotary movements relative to the movable contact and having means loosely connected to said movable contact for driving same; a reciprocable rod; ratchet provisions between the rod and the driving means cooperating to rotate the driving means in steps intermittently, said ratchet provisions being so arranged that the driving means will be moved one step in one direction of rotation only upon full actuation of the rod in either direction; and resilient means disposed between the contact and the driving means for urging the movable contact toward the stationary contacts and the driving means against the rod and thereby maintain the ratchet provisions effective.

25 5. An electric switch including, a switch casing; a closure for the casing carrying stationary contacts arranged in a circular row; a stud supported by the casing and the housing; bridge means supported on a carrier rotatably and axially movable on the rod; a manually operated plunger extending into the casing and having a slot straddling the stud whereby the plunger is guided in straight line movement; a disc rotatably and axially movable on the stud; ratchet provisions between the plunger and the disc of which a part is provided on each side of the slot and a circular row of abutments is provided by the disc; means associated with the disc having a slidable spline connection with the carrier whereby the disc and carrier rotate together at all times while permitting axial movements relative to each other; resilient means carried by the stud functioning to urge the carrier toward the closure and at the same time press the disc against the plunger whereby one part or the other of the ratchet provisions provided by the plunger will cooperate with one abutment of the disc to rotate the latter in one direction of rotation only upon manual operation of the plunger in either direction.
